ABSTRACT OF THE DISCLOSURE

A conversion, magazine-adaptor for use on bolt-operated, single shot firearms in which one or more supplemental rounds are gravity-fed to an upwardly opening receiver on the firearm after a spent cartridge case is ejected due to bolt actuation; novel supplemental magazine overlying the upwardly opening receiver and including dual acting spring means for automatically gravity dispensing fresh cartridges into a receiver of a single shot fire arm to convert it into a repeater type.

BACKGROUND OF THE INVENTION

The present invention relates generally to applicant's United States Letters Patent 3,394,481, issued July 30, 1968, and titled Adaptor for Converting a Single Shot Firearm Into a Two Shot Repeater.

The present invention fulfills an unsatisfied demand for an effective and inexpensive conversion attachment for converting single shot firearms to the repeater type.

SUMMARY OF THE INVENTION

It is therefore the main object of this invention to supply an attachment with a very simple mechanism, and with a low production cost, that will allow converting a single-shot firearm into a repeater, as long as the firearm is actuated by means of a bolt mechanism.

Another object that is of no less importance than the above and which is sought by means of this invention, lies in providing an attachment of this sort that makes use of the force of gravity for the rapid replacement of the spent cartridge with a live one within the firing chamber of the barrel of the firearm, but in such a way as to maintain mechanical control over the replacement, which is what makes the attachment properly a loader for two shots or more.

In fact, were there no such control over the force of gravity, such as was the case of the previously proposed solutions, including the one that motivated the previous request for a patent as mentioned above, the attachment could only serve to hold one cartridge in addition to the one in the chamber, thus doubling the fire power of the firearm. The placement of more than one cartridge in said attachment meant that all would drop out at the same time under the force of gravity, and since the chamber could obviously receive only one, the rest would fall away from the firearm.

In order to achieve the objectives being pursued, then, the present invention is intended to provide an attachment to load single-fire bolt-loading firearms, or in other words, a loader, for several live cartridges, that can be easily adapted to the part of the barrel known as the breech or receiver mechanism, employing mechanical means to control the delivery of the cartridges from the loader. This is achieved by use of the force of gravity once the breech is opened and emptied by the action of the bolt and in such a way that the cartridges are delivered one by one with the delivery of each one corresponding to one operating cycle of the bolt.

BRIEF DESCRIPTION OF THE DRAWINGS

The nature of the invention, will be more easily understood when it is considered in conjunction with the accompanying drawings wherein:

- 5 FIG. 1 is a perspective view of an improved loading attachment according to the invention, partially broken away for purposes of clarity;
10 FIG. 2 is a perspective view showing the attachment of FIG. 1 mounted in an operative position on the barrel of a firearm, adjacent the breech or receiver thereof;
15 FIGS. 3 and 4 are perspective views taken respectively from the side and top of a portion of the barrel of a firearm upon which the attachment of the invention has been mounted, showing a modified embodiment of the invention;
20 FIGS. 5, 6 and 8 are perspective views of slightly modified loading attachments, incorporating a control spring similar to that of the embodiment of FIGS. 3 and 4, and illustrating modified cartridge magazines; and
25 FIG. 7 is a perspective view of the control spring used in the embodiments of FIGS. 3-6 and 8.

With regard to the above mentioned FIGS. 1 and 2 showing the first modality of the invention, the improved loading attachment includes a clamp 10, made preferably of cold-stamped steel sheet to provide the most suitable form for attachment to the receiver 11 of the bolt mechanism of the firearm. The clamp is provided with drill holes 13 for its rigid attachment to said receiver 11 of the bolt mechanism by means of a screw. The upper portion of this clamp becomes the magazine or storage 14 for the cartridges, and it is provided with the usual slot 16 in the rear portion to facilitate cartridge placement.

The control device, then, for delivering the cartridges one by one as the bolt mechanism 12 is actuated in its customary reciprocal motion, in this first modality of the invention, consists of a dual action leaf spring with the first upper portion 17 bent inwardly at a right angle and with the end cut along a straight line. A second lower portion 18 is also bent inwardly at a right angle, but the end is cut diagonally at 19, both vertically and horizontally. These two bent portions 17 and 18 are the teeth of the dual action control device, with a common spring action. The rest of the spring, which would be the back 20, continues downward in a partial clamp 21, which coincides or generally overlaps the clamp 10 of the magazine 14 of the loader and is attached together with it and by means of the same screws to the receiver of the firearm, through holes 22.

50 As will easily be seen, the operation of the control device for the delivery of the cartridges 15 from the loader magazine 14, is obtained in combination with the back and forth motion of the bolt 12. As the bolt is moved forward, it engages the lower tooth of the spring on diagonal cut 19 of portion 18, displacing the tooth outwardly. This movement is transmitted to the upper tooth 17 by means of the back 20, so that this upper tooth, which normally extends into the magazine 14 through slot 23, is displaced outwardly of slot 23. Thus the lowermost cartridge stored in the magazine gravitates downwardly as soon as it overcomes its inertia. Proceeding in this manner, when the bolt 12 is drawn backward after the shot, or stated otherwise, when the receiver of the firearm is opened and the spent cartridge case is expelled by the ejector 24 so that the breech is again free, the lowermost of the stored cartridges drops at once into the receiver. At this same instant, when it is no longer opposed by the withdrawn bolt, the lower tooth 18 of the control spring recovers its original position within the receiver and also draws upper tooth 17 back to its original position within the magazine of the loader, thus introducing an obstacle so that the remaining car-

tridges press against the now lowermost cartridge that replaced the cartridge that dropped into the receiver chamber to take the place of the spent cartridge, and at the same time they exert a downward pressure on it. It should be noted that said lower tooth 18 of the control spring acts through slot 25 in magazine 14 in the placement of the cartridges 15. This slot coincides with a lateral notch 25' opening into the portion of the barrel that we have referred to as receiver 11 for the bolt mechanism 12.

In the modality illustrated in FIGS. 3, 4, 5, 6, 7 and 8 (primed reference numerals will be used to indicate similarly functioning structure), the control device or escapement that regulates the passage or delivery of the cartridges 15 from the magazines of the loaders, is substantially equivalent in construction and operation to the device in the modality shown in FIGS. 1 and 2. It differs, however, in the construction of the dual action spring, instead of being of suitably stamped sheet, is made of wire with the bends necessary to conform to upper tooth 17 and lower tooth 18. This wire elements is provided with an extension 26 so as to allow its being held under due pressure between the loader magazines 14'-14''' and the receiver 11 of the bolt mechanism 12.

In the same modality to which we now refer, it would be feasible to have clamp elements 10' that attach magazines 14'-14''' of the loader to receiver 11 of the bolt mechanism 12 made of a simple metal band, preferably of steel and further provided with drill hole 13' for the corresponding screw.

It also seems worthwhile pointing out that in any of the modalities of the control device for the delivery or release of the cartridges from the loader of the magazine to the receiver of the bore of the barrel of the firearm, different design forms are feasible for specific purposes in holding the cartridges within the magazine. Thus, the design shown in FIG. 1 could be used, where the forward part of the magazine is completely rounded and there is a single slot 16 in the rear, or the design shown in FIG. 5 where the forward portion of the magazine is rounded and the rear portion is closed, or the design shown in FIG. 6, where the forward portion of the magazine is rounded with a large portion 27 cut back, or the design shown in FIG. 8, where the forward part of the magazine is rounded with a portion 27' cut back at an angle and the rear is complete, but on the other hand the side walls have been provided with entrance openings 28.

Finally, it should be indicated that the details that have been described and illustrated correspond to the practice of improvements in the invention that are in keeping with what would be preferable, but by no means do these set the limits of this invention, which will be defined in the justification set forth in the following claims.

What is claimed is:

1. A firearm repeater loader for converting single shot firearms having an operating bolt and an upwardly opening cartridge receiver, comprising:
a member having means for mounting the same on a firearm adjacent the cartridge receiver thereof, said member including a loader magazine for containing at least one supplemental cartridge oriented in the general position for manual insertion of a cartridge into said receiver, said loader magazine including displaceable abutment means normally extending into said loader magazine for retaining a cartridge thereabove and against gravi-

tational descent from said loader magazine into said receiver, said abutment means including a first portion engageable by the operating bolt when operated for dispensing a cartridge into said receiver,

5 said abutment means including a second portion spaced from said first mentioned portion and operatively connected thereto for permitting the gravitational release of subsequent cartridges to a lowermost, dispensing position in said loader magazine.

10 2. The structure as claimed in claim 1, in which said abutment means comprises a dual action spring, said first and second portions comprising teeth extending into said loader magazine, the lowermost of said teeth including an oblique edge portion normally disposed in the path of movement of the operating bolt of the firearm, said teeth being displaceable out of said loader magazine when a cartridge case is ejected from the firearm.

15 3. The structure as claimed in claim 2, in which said dual acting spring comprises a leaf spring and said teeth are integral portions thereof extending generally at right angles into said loader magazine from a back portion of said leaf spring.

20 4. The structure as claimed in claim 3, in which said loader magazine comprises a receptacle for receiving at least one cartridge therein, said receptacle including a lower depending portion for mounted engagement with the lower portion of the receiver of a firearm, said back portion of said dual acting spring including a depending mounting portion generally overlying said mounting portion of the loader magazine.

25 5. The structure as claimed in claim 2, in which said dual action spring comprises a wire element, said teeth being skeletonized and defined by upper and lower bent portions of said wire element.

30 6. The structure claimed in claim 5, in which said wire element includes an elongated projection which will be disposed adjacent the outer surface of the receiver upon which the loader attachment is mounted.

35 7. The structure as claimed in claim 1, in which said loader magazine comprises an upwardly opening receptacle for manually receiving cartridges therein.

40 8. The structure as claimed in claim 7, in which said receptacle includes a rearwardly opening slot portion for permitting manual insertion of cartridges therein.

45 9. The structure as claimed in claim 7, in which said upwardly opening receptacle includes closed forward and rear wall portions.

50 10. The structure as claimed in claim 7, in which said upwardly opening receptacle includes a skeletonized forward portion for visually ascertaining the number of cartridges disposed in said upwardly opening receptacle.
